Primary Examiner — Lauren D Mcvey(74) *Attorney, Agent, or Firm* — Oliff PLC(57) **CLAIM**

The ornamental design for a printer as shown and described.

DESCRIPTION

FIG. 1 is a top, right perspective view of the printer;
 FIG. 2 is a front elevational view thereof;
 FIG. 3 is a rear elevational view thereof;
 FIG. 4 is a left-side elevational view thereof;
 FIG. 5 is a right-side elevational view thereof;
 FIG. 6 is a top plan view thereof;
 FIG. 7 is a bottom plan view thereof;
 FIG. 8 is a bottom, left perspective view thereof;
 FIG. 9 is a detail view of the portion indicated as "9" in FIG. 1; and,
 FIG. 10 is a detail view of the portion indicated as "10" in FIG. 8.

The evenly spaced broken lines depict unclaimed parts of the printer and form no part of the claimed design. The dot-dash chain lines depict a boundary of the claimed subject matter and form no part of the claimed design. The dot-dot-dash chain lines forming rectangular shaped boxes around certain portions of FIGS. 1 and 8 depict areas shown as detail views in FIGS. 9 and 10, and form no part of the claimed design.

1 Claim, 10 Drawing Sheets(56)
